UNITED STATES PATENT OFFICE.

LEWIS P. HALLADAY, OF MARION, INDIANA, ASSIGNOR TO PHILIP MATTER,
OF SAME PLACE.

DESIGN FOR A SCALE-BEAM.

SPECIFICATION forming part of Design No. 33,369, dated October 16, 1900.

Application filed April 24, 1899. Serial No. 714,319. Term of patent 7 years.

To all whom it may concern:

Be it known that I, LEWIS P. HALLADAY, a citizen of the United States, residing at Marion, in the county of Grant and State of Indiana, have invented and produced a certain new and useful Design for Scale-Beams, of which the following is a specification.

My invention relates to a new and original design for scale-beams, of which the following is a description, reference being had to the accompanying drawing, wherein the figure is a view of a scale-beam embodying my design.

My design relates to scale-beams for computing-scales; and it consists of a beam made

up of the cylindrical part A and the projecting flattened portion B. The circular beam proper has a longitudinal projection and also an enlarged end piece at its outer end and beyond that a smaller end, and these features constitute the essential features of my design. 15 20

I claim—

The design for a scale-beam as herein shown and described.

LEWIS P. HALLADAY.
